(76) Inventor: **Philo Clinton Curtis**

*Philo Clinton Curtis
Gatting Patent*

The Schedule referred to in this Gatting Patent and making part of the same containing a description in the words of the said Philo Clinton Curtis himself of his invention in the Water-Gat.

The loom or frame of the loom is composed simply of four pieces of timber two of which I term the end pieces and two the side pieces or bays, two end pieces are proportioned in length to the weath that is necessary to be woven and have a mortise in each end to receive the side bays in the centre of each end piece there is a tenon that enters the mortise in the end pieces so that when put together they will form a square or an oblong square the frame may be either pinned or secured together with joint bolts; in or near the centre of this frame I place a wheel the Diameter of which is large enough to slide on to the frame, within this wheel I hang two rollers which supports the beam's for springing the web within this frame and near each end I place the cloth and yarn beams or rollers within the wheel and between the cloth and yarn beams, I hang the lathe or battin on rods or in a groove and let it slide parallel with the loom or side bays between the yarn and cloth beams I place two rollers or rods which may be wound with wire or formed into a scroll in any other way to the right and left from the centre of the loom between the lathe and cloth roller which serves for templing the cloth; to operate the lathe there is a roller placed in back of the yarn beam that extends from side to side of the frame and has a lever in the centre that is operated upon by a circular inclining part of the loom there is a connection from the lathe to the roller at each end of the lathe by two pitman's that are connected to two that lever in the end of

the rollers as the loom is operated upon by the inclining plane it moves the lathe back as far as is necessary to let the shuttle pass and then continues on a circular line parallel with the end of the loom in sufficient length of time for the shuttle to sweep through the web which then is a sudden stop in the place which allows the spring which operates the lathe to draw it up the spring may be fastened in the centre of the end piece and allowed to extend over the yoke beam on a circle to a piece that rises from one side of the lathe to the other back of the beams the rollers which serve as temples may be moved by a short lever in the roller that moves the lathe to operate upon a slide that reaches to the temple rollers and has a hand or pull on the end to operate in a ratchet wheel that is on the temple roller or not so as to turn it around and spread the claw each way from the centre. I place two small wheels on these rollers near the end with teeth that make into each other so that turning the one turns them both; for holding the shuttle. I have two boxes by the side of the wheel over a ravine thru the side bars of the loom which boxes are long enough to receive the shuttle over the end of the box there is a slide that is connected to a short lever on the side bars that rests on a pivot, on the end of this lever farthest from the box there is a spring of such strength that the weight of the shuttle when it stands perpendicular will over power it and allow the lathe to pass over the end thereof and prevent it from passing out of the box until the loom has turned and drawn the lathe back and raised the shuttle up so that its own weight will cause it to pass thru the web, the lever that is operated upon by the shuttle answers the purpose of stopping the loom if the shuttle fails of dropping into the box the spring on the end of the lever will hold that end out from the frame so that when it passes to a certain point it will catch the sliding pulley which

which takes the shape that passes around the big wheel and stops the loom, in order to sprung the web when may be two shafts and two pullets within the wheel above the roller that supports the bairns which shafts may be supported by the wheel, on one end of each of these shafts there is a lever that extends to the out edge of the wheel there is a circle part way around the large wheel that is fastened to the out side frame that supports the loom which these levers alternately slide upon there is a connection from the pullets to the bairns rollers by a cord strap or chain so that when one of the levers goes upon the circle it draws the other back and springs the web, in order to hold the web and take it up as it is woven I place on one end of the cloath roller and yarn beam a wheel with teeth or cog the one on the cloath roller turns loose and the roller is turned with a cord that is fastened to a pin in the wheel on the roller and is wound a number of times around the roller and fastened to the pin again, by means of sprung gradually some lengthwise of the loom I have a rod that has two screws or rooms on it one to each wheel on the bairns so that by turning the rod it lets down the webs and takes up the cloath, on one end of the rod that has the rooms or screws on I place two ratchet-wheels one of which is permanently attached to the rod and which I turn the taking up wheel the other which is near the former round round the rod being prevented however from changing its position unless operated upon by the hand or pull by means of a clamp or spring fixed to the side of the loom the hands or hands which act upon these ratchet-wheels are operated by a short lever or staff in the roller that operates the lathe they are kept down upon the wheels by means of springs and have a cord or communication rising from one of them to the end of a particle braker and descending from

from the opposite end of said handle to the other part or hand so that when one hand is depressed by the spring into the notch of its ratchet-wheel one only of the hands or palls acting upon its wheel at one time; the handle in which these ratchets which move round the axle has its periphery so divided into teeth that the full swing of the lathe just passes the fall or hand so far back as to remove it one notch and suffer the hand to fall thence and so as to keep the other fall or hand which would act upon the taking up wheel out of the teeth thereof. When however so much of the webbe is woven that the lathe cannot have its full swing the fall or hand does not cut the notch in the moving ratchet-wheel but will fall into the notch thereof and the moving back-end of the lathe will propell the ratchet-wheel by means of the hand or fall and so much of the webbe will be round upon the rollers as will allow the lathe bottom again to have its full swing and the hand or the moveable ratchet-wheel to have its operations the frame calculated to support this loom may be simply posts set in the building when it is used for the pivots to rest and turn in, or a frame calculated for that purpose. The box for the shuttles may be either attached to the lathe and move with it or fastened to the side pieces or bars of the loom. The spring to move the lathe may be in any form best calculated for the business to be performed the power applied to these looms may be done either by steps round the big wheel on the loom or by a wheel or one of the bearings. the power employed to move these looms may be either manual or that of horses using water or steam as shall be thought most convenient in the factories where they shall be introduced.
